(54) **TYPES, MUSIC**

(76) Inventor: **Uri K. Hill**

To all whom these Presents shall come, greeting,
Know, that the annexed is a true copy of a Patent granted
to Mr. W. Hill on the 7th January 1837, for his Improve-
ment in Musical Types.

In testimony whereof I, George Clay, Secretary of
State of the United States, have hereunto sub-
scribed my name and caused the Seal of the
Department of State to be affixed.

Done at the city of Washington this twenty sixth day
of January A. D. 1837, and of the Independence of
the United States of America the 57th

George Clay

The Schedule referred to in these Letters Patent and making part
of the same containing a description in the words of the said
Mr. W. Hill himself of his improved Musical Types.

Mr. W. Hill hath invented a new kind of music
type improved in its construction & application in the
following particulars.

1st In the separating the type into points the
rule from that which prints the lines.

2nd In the shapes of the notes, and likewise in
application of those shapes to designate the mi, fa, sol,
la, of this country and of England, the do, re, mi, fa,
sol, la, si, of Italy; or the si, re, mi, fa, sol, la, si, of France.

3rd In the designating the changes of the mi according
to use in the English Solmization, and thereby showing
the changes of the octave by means of these shapes, or
as by any other shape differing from the common shape,
as properly designating any of the above mentioned
syntables.

The notes, and lines and spaces are each separated

I warrant that the notes may be set up without the lines and impressed on ruled or printed lines, or the lines ruled or printed after the notes are printed.

The different shapes of the notes pertain to their heads. These are as follows: — The round head represents the note in an ascending oval the far, a horizontal oval the sol, and a descending oval the la. — When the far sol, &c, is repeated it is said to appear flat. — When the flat note is used in the head of the note which completes the line, the shape used to denote the two primitive sounds according to the French and Italian classifications. — This type differs from the common music type in the following particulars. —

In the common type, each type contains the lines and spaces together with the note. — In this type the notes and lines are on separate types. —

In the common type, the notes cannot be set without the lines and spaces. In this either the notes or the lines may be set up separately. —

Two of the shapes here given have been used in common music, but were never used to designate the same syllables in ours, or any syllable in the foreign languages. — The round and angular shapes have been used, in this country to express the note, flat, la, but never used to designate the state of the culture when the note is changed by modulations.

In the common type the notes can only be impressed together with the lines. — In this type the notes may be impressed on ruled or printed lines, or the lines ruled or printed after the notes are printed.

With respect
Wm. H. Hill
